UNITED STATES PATENT OFFICE.

THOMAS LUND, OF BEVERLY, MASSACHUSETTS, ASSIGNOR TO UNITED SHOE MACHINERY CORPORATION, OF PATERSON, NEW JERSEY, A CORPORATION OF NEW JERSEY.

NAIL DISTRIBUTOR.

Application filed April 14, 1924. Serial No. 706,403.

The present invention relates to apparatus for supplying nails to machines in which they are to be utilized, as those for attaching heels to shoes. It more particularly has to do with apparatus adapted to separately deliver nails from independent sources, this allowing, for example, the driving by a heeling machine of nails of such varying lengths as will best secure to a shoe different portions of a heel.

The invention has as an object the provision of a nail-distributor of the character indicated above, which is simple and effective and which involves relatively slight departures from existing organizations, as that which is the subject of Patent No. 1,005,303, Pope, October 10, 1911, so that conversion from one to the other may readily be accomplished.

With this object in view, a feature of the invention involves a distributing apparatus having a plurality of nail-receptacles, and a movable conveyor along which nails are advanced, said conveyor being provided with separated conveying portions respectively individual to each receptacle and a conveying portion common to the separated portions. The conveyor may be in the form of what is commonly termed a "washboard", this being a nail-way made up of bars each having a channel arranged to deliver to a conduit supplying the machine which is to use the nails. The body-portion of the conveyor common to the receptacles may be constructed, mounted and actuated as in the distributor for operating upon nails of a single length, the principal departure from standard practice lying in the connection of the plural receptacles to this body-portion.

As another feature of the invention, there extends adjacent to the nail-receiving channels of the body-portion of the conveyor a member for simultaneous contact with nails from all the plural receptacles. Such an arrangement may be utilized both in connection with a nail-reversing device, and with a nail-stop more directly associated with a discharge device, which controls the passage of nails from the delivery-end of the distributor. It lends itself, as does the conveying system, to the adaptation of standard apparatus to the new purpose of distribution of nails of diverse lengths. Since it is desirable to adjust such contact members in

the operation of the apparatus, I provide for 55 the proper effect of said members upon the nails coming from different receptacles by furnishing the member, whether it be that for the reversing device or for the stop device, with portions adjustable to correspond 60 to the conveyor-branches from the receptacles. When the contact member is that associated with the stop device, I combine with its independently movable portions means arranged to adjust each separately in different directions toward and from the discharge device. This furnishes, in a distributor supplying different lengths of nails, a stop device which may be positioned not only in accordance with more than one 70 length, but may also be caused to co-operate with the discharge device to the best advantage for each length.

Other features of the invention will be developed in the following specification, illustrated by the accompanying drawings, in which

Fig. 1 shows in perspective a particular embodiment of my improved distributor;

Fig. 2, a partial top plan view of the delivery-end of the conveyor with the discharge and stop devices;

Fig. 3, a longitudinal, vertical section through this portion of the apparatus on the line 3 of Fig. 1.

Fig. 4, a perspective view of the stop device with its elements separated; and

Fig. 5, a top plan view of the base with the actuating elements for the nail-receptacles mounted thereon.

A supporting base 10 is adapted for attachment to the frame of a heeling machine to which it may be desired to supply nails. As in the patent previously mentioned, there are journaled upon an upper frame-portion 95 11, carried on the support and which may be identical with the corresponding element of an apparatus designed for supplying nails of but one length, front and rear shafts 12 and 14, respectively, upon which are fixed 100 rock-arms 16 receiving portions 17 of a nail-way or conveyor 18. The conveyor is reciprocated to effect the advance of the nails along the ways by an eccentric-rod 20 from a power-shaft 22 journaled transversely of 105 the frame 11. The nail-way may be of the well-known washboard type, having series of longitudinally extending adjacent bars

24, in the upper edges of which are nail-receiving and conducting grooves or channels 26. The nail-way is shown as formed in two sections 28 and 30 lying in substantially parallel planes or extending in the same general direction, the former furnishing a body-portion which is in all essential respects identical with that of the Pope patent and having the bars 24 parallel to each other. This portion or section is continued rearwardly by the section 30, which includes a delivery-throat 32 similar in arrangement to the section 28, and diverging branches 34, 34, in each of which the bars are parallel to one another, constituting two groups, which terminate, as they converge in the direction of progress of the nails, in corresponding groups of parallel bars in the throat and body-portion. Each of the branches 34 extends into the open side of a receptacle 36, shown as the customary drum adapted to contain nails in bulk and elevating and dropping them into the conveying channels 26. The drums preferably have their axes at right angles to each other, and are carried upon a rearward extension 38 from the base 10. Upon the extension are pairs of bearings 40, 40 for supporting parallel shafts 42, 42, these pairs of shafts being at right angles to each other. Sleeves 44, upon which rest flanges 46, 46 of the drums, have peripheral grooves 47 to receive the rear flanges and retain the drums against displacement. One shaft of each pair is rotated through spiral gearing 48 from a shaft 50 extending horizontally from front to rear of the base and its extension. The shaft 50 is, in turn, connected by bevel gearing 56 to a vertical shaft 54 rotatable in the base and joined by spiral-gearing 52 to the main shaft 22. The shafts 42 of each pair are connected to move together by a belt 55 running in grooves 57 formed in the sleeves 44. By the shafting and gearing, the sleeves 44 are maintained in constant rotation in the same direction during the operation of the machine, communicating this motion to the drums, thereby causing them to lift the nails and drop them into the grooves of the branching conveyor-portions 34, so these are continuously supplied.

Associated with the body-portion 28 of the nail-way is a reversing device 58. This consists of a plate or member 60 having grooves 62 and supported at the forward extremity of the throat 32 of the conveyor-section 30 and over the rear of the section 28, being spaced from the former at 64. The grooves 62 in this plate are alined with those of the conveyor. This reversing device acts in the usual manner to insure all the nails passing along the grooves 26 being delivered with their heads foremost. The space at 64 is such, that nails traveling along the channels under the influence of the re-

ciprocation of the conveyor, and entering this from the throat 32 with their heads in advance, will overbalance and fall into the grooves of the section 28, without contact with the reversing device. If, however, the points are foremost, gravity does not act until the nails have bridged the space 64 with their forward extremities resting in the grooves 62, they then continuing the advance until the heads leave the throat-grooves, again falling head-down. To adapt the reversing device to act effectively upon nails of different lengths, the plate is adjustable to vary the width of the space 64 by means of racks and pinions 65 connecting it to a shaft 66 arranged for manipulation by the operator. By moving the plate toward or from the adjacent extremities of the grooves in the throat 34, the width of the space 64 may be varied to cause the correct co-operation of the reversing plate with nails of the particular length at that time passing through the apparatus. This provides for nails from the group of channels in one of the branches 34. Since the other group delivers another length of nail, the plate 60 has alined with the second group an independent section 68 mounted upon the plate for movement in the same direction thereas, and being fixed in place by a slot-and-screw connection 70. The grooves in this plate-section 68 correspond to those of the other conveyor-branch 34, and the section may be adjusted, regardless of the position of the main section, to properly reverse the nails upon which it acts.

From the forward extremities of the channels in the body-portion 28 of the conveyor, the nails pass to a discharge device 72, which controls their time of delivery to conduits 74 leading to the machine supplied. This device includes a roll 76 journaled transversely at the end of the conveyor-channels and having a series of passages 78 respectively alined with such channels. The roll is oscillated through connections 80 from a cam 82 upon a shaft 84 journaled at one side of the frame 11. This shaft is rotated by gearing 86 from the main shaft 22. Upon leaving the channels 110 of the conveyor, the nails are received by the passages 78, which are normally alined with said channels, and there held for an interval determined by the contour of the cam 82, the roll being turned at the proper time to further incline the passages 78 and discharge the rolls into the conduits 74.

To hold the nails upon the device 72 ready for discharge, they contact with a stop device 88. This device includes a body-portion, which may consist of a plate 90 extending across the extremity of the conveyor parallel to the axis of the roll 76. The plate is connected by racks and pinions 92 to a shaft 94 under the control of the 120

operator, the rotation of this shaft producing an adjustment of the plate toward and from the discharge-roll. Movable in ways 96 extending transversely of the plate is a slide 98 having a depending portion 100 engaged by a screw 102 threaded into the plate below the slide. By this means, the slide may be varied in its relation to the discharge-roll independently of a corresponding 10 adjustment of the plate 90. The slide is recessed at 104, and at 106 the plate is similarly recessed. In the ways thus provided slide carrier-bars 108, 108, pressed normally out toward the discharge-roll by 15 springs 110 located between the carrier-bars and the inner walls of the recesses. The extent of movement of the carrier-bars is limited by pins 112 fixed in the slide and plate and extending across the recesses 20 through slots 114 in the carrier-bars. Pivot 25 at 116 upon each carrier-bar is a stop-bar 118, which, in the nail-retaining position, lies over a downwardly inclined surface 120 at the forward ends of the passages 78, each of the bars presenting a stop-surface throughout its entire length equally distant from the passage-openings. Each bar-section is adjustably supported upon its pivot by a screw 122 threaded vertically through the carrier-bar and having at its lower end an enlargement 124 for engagement with a horizontal slot at the inner side of the corresponding bar. Each screw may be secured in its adjusted position by a lock-nut 126. Upon turning either of the screws, its bar may be raised or lowered, so that its relation to the surface 120 of the discharge-roll may be altered. There thus exists a capacity for adjustment of one of the stop-bars toward and from the passages 78 in the nail-roll, these passages corresponding to a group of the nail-channels continuing those of one of the conveyor-branches 34. This adjustment is effected by moving the plate 90 as a whole by means of the shaft 94. The other stop-bar co-operating with the group of discharge-roll-passages belonging to the other conveyor-branch is independently adjusted by means of the screw 102. Thus, the space between the bars and the ends of the nail-channels may be brought into accord with the lengths of nail delivered by such channels. Because the surface 120 is downwardly inclined, 55 such an adjustment as that just described varies the vertical relation of the lower edge of each stop-bar to the surface. Unless this were compensated for, a space would be opened below a bar when it was adjusted outwardly, which would tend to interfere with the proper arresting of the movement of nails and their discharge. The raising or lowering of the stop-bars by the screws 122 permits the maintenance of a uniform 60 distance between the bars and inclined sur-

face, the adjustment being independently accomplished for the respective bars. This is rendered necessary by their varying positions horizontally, because of their co-operation with nails of two lengths.

In using the apparatus, nails of the desired lengths are put in the two drums 36, 36, to be elevated thereby to the grooves of the converging conveyor-branches 34, 34. Passing down these to the throat 32, they fall through the space 64, reversed, if necessary, by a device 58, so their heads are all pointing forward. To provide for the proper action of this reversing device upon the particular lengths of nails which may have been placed in the drums, the plate 60 and the section 68 are separately adjusted, either by turning the shaft 66 or altering the position of the upper section upon the plate by means of the slot-and-screw connection 70. Further advancing along the grooves of the body-portion 28, the nails enter the passages 78 of the discharge device 72, being temporarily stopped by the bars 118. The proper distance of these bars from the aligned groups of channels conveying the two lengths of nails is provided for by either movement of the shaft 94 to shift the plate as a whole, or the screw 102 to vary the position of the slide 98. As the relation of the bars to the surface 120, upon which the nails rest in the discharge-roll, is changed by this movement of the bars, the latter are correspondingly raised or lowered by the screws 122 until they are in position to best retain the nails for delivery. Thus held, the loads are successively discharged by oscillation of the roll 76 in an anti-clockwise movement, as viewed in Fig. 3 of the drawings, into the conduits 74, passing therethrough to the loading mechanism of the heeling or other machine supplied. Since, in the main, the elements of my improved nail-distributor for operating upon nails of different lengths are identical with those of an apparatus adapted for use in connection with a single length of nail, a manufacturer of both types of apparatus will be required to produce and carry in stock a much less number of parts than were the designs unlike. It is also desired to point out that generally the structure is simple and efficient, the arrangement not being complicated by the increase in the service performed.

Having described my invention, what I claim as new and desire to secure by Letters Patent of the United States is:

1. A nail-distributor comprising a plurality of nail-receptacles, a nail-conveying device having a conveying portion individual to each receptacle, said portions being separated from each other, and a conveying portion common to the separated portions, and means for moving the device to advance nails along the conveying portions.

2. A nail-distributor comprising a plurality of nail-receptacles, and a nail-conveying device having portions converging toward each other from the receptacles and a common portion simultaneously to which the converging portions deliver, all of said portions extending in the same general directions.
3. A nail-distributor comprising a plurality of receptacles, and a reciprocatory nail-way provided with channels converging from each receptacle to parallel channels.
4. A nail-distributor comprising a plurality of receptacles, conduits to which the nails are to be supplied from the receptacles, and a nail-way providing a supporting surface to which the nails are delivered by the receptacles and from which said nails fall into the conduits, there being a body-portion of the nail-way delivering to the conduits and branches diverging from the body-portion to the receptacles.
5. A nail-distributor comprising a plurality of receptacles, conduits to which the nails are to be supplied from the receptacles, and a nail-way interposed between the receptacles and conduits, there being a body-portion having a channel delivering to each conduit and branches diverging from the body-portion and each provided with parallel channels communicating with the channels of the body-portion.
6. A washboard for nail-distributors comprising a body-portion, and branches diverging therefrom, the body-portion being made up of groups of parallel bars each provided with a nail-conveying groove and each group of bars being continued into one of the branches in which the grooves diverge from those of the other branch.
7. In a nail-distributor, a plurality of nail-receptacles, a nail-conveyor having a body-portion and branches diverging therefrom to respective receptacles, and a member extending across the body-portion of the conveyor and arranged for simultaneous contact with the nails proceeding from the receptacles by all the branches.
8. In a nail-distributor, a plurality of nail-receptacles, a nail-conveyor having a body-portion and branches diverging therefrom to respective receptacles, and a member extending across the body-portion of the conveyor and arranged to contact with the nails proceeding from the receptacles by all the branches, said member having portions adjustable to correspond to the separate branches.
9. In a nail-distributor, a plurality of nail-receptacles, a nail-conveyor having a body-portion providing nail-supporting surfaces with branches diverging therefrom to respective receptacles, and a nail-reversing device co-operating with the body-portion of the conveyor.
10. In a nail-distributor, a plurality of nail-receptacles, a nail-conveyor having a body-portion and branches diverging therefrom to respective receptacles, a nail-reversing device co-operating with the body-portion of the conveyor, and means arranged to adjust the reversing device with respect to the entire body-portion, said device having a portion corresponding to one of the branches and adjustable independently of the remainder of the device.
11. In a nail-distributor, a plurality of nail-receptacles, a nail-conveyor having a body-portion and branches diverging therefrom to respective receptacles, a discharge device co-operating with the body-portion of the conveyor at the extreme removed from the receptacles, and a nail-stop associated with the discharge device.
12. In a nail-distributor, a plurality of nail-receptacles, a nail-conveyor having a body-portion and branches diverging therefrom to respective receptacles, a discharge device co-operating with the body-portion of the conveyor at the extreme removed from the receptacles, a nail-stop associated with the discharge device, and means arranged to adjust the stop toward and from the discharge device, said stop having a portion corresponding to one of the branches and adjustable independently of the remainder of the stop.
13. In a nail-distributor, a movable discharge device for the nails, a stop member co-operating with the device and having independently movable portions, and means arranged to adjust each portion separately in different directions both toward and from the discharge device.
14. In a nail-distributor, a movable discharge device for the nails, and a stop device having a body-portion, means arranged to adjust the body-portion with relation to the discharge device, a member mounted upon the body-portion for contact with the nails and means arranged to adjust the member upon the body-portion in a plurality of directions both toward and from the discharge device.
15. In a nail-distributor, a movable discharge device for the nails, and a stop device co-operating with the discharge device and having a body-portion, a plurality of carrier members movable upon the body-portion, a stop member movable upon each carrier member and means arranged to independently adjust the position of each stop member upon its carrier member.
16. In a nail-distributor, a movable discharge device for the nails, and a stop device co-operating with the discharge device and having a body-portion, means arranged to vary the position of the body-portion, a slide movable upon the body-portion, means arranged to vary the position of the slide,

carriers yieldable upon the body-portion and slide, stop-bars movable upon the body-portion and slide and means arranged to move the stop-bars upon their carriers.

5 17. In a nail-distributor, a nail-conveyor, a support upon which the conveyor is movable, said support being provided with an extension, a plurality of nail-receptacles mounted upon the extension and delivering 10 to the conveyor, and driving means for the conveyor carried by the support and connected to the receptacles.

18. In a nail-distributor, a movable nail-conveyor, a support therefor provided with a rearward extension, a plurality of nail-drums rotatable upon the extension, driving mechanism for the conveyor carried by the support, and connections rotatable upon the extension and communicating motion from the driving mechanism to the drums. 15 20

In testimony whereof I have signed my name to this specification.

THOMAS LUND.
